(57) **CLAIM**

The ornamental design for a spinal therapy apparatus, as
shown and described.

DESCRIPTION

FIG. 1 is a left, front perspective view of the spinal therapy
apparatus, showing our new design;

FIG. 2 is a left side view, thereof;

FIG. 3 is a left, rear perspective view, thereof;

FIG. 4 is a rear view, thereof;

FIG. 5 is a right, rear perspective view, thereof;

FIG. 6 is a right side view, thereof;

FIG. 7 is a right, front perspective view, thereof; and,

FIG. 8 is a front view thereof.

In the drawings, the broken lines are for the purpose of
illustrating portions of the spinal therapy apparatus that form
no part of the claimed design.
